UNITED STATES PATENT OFFICE.

ISAAC H. WEINBERG AND CHARLES F. BISBING, OF NEW YORK, N. Y.

UMBRELLA PARASOL.

Application filed February 16, 1922. Serial No. 537,017.

To all whom it may concern:

Be it known that we, ISAAC H. WEINBERG and CHARLES F. BISBING, citizens of the United States, and residents of the city of New York, borough of Manhattan, in the county of New York and State of New York, have invented a new and Improved Umbrella Parasol, of which the following is a full, clear, and exact description.

10 This invention relates to improvements in umbrellas or parasols, an object of the invention being to provide an improved construction of umbrella or parasol, whereby the cover, when in open position, has a 15 canopy appearance which is extremely attractive and ornamental.

20 A further object is to provide improvements in the construction of an umbrella or parasol, whereby the cover connected to the ferrule of the umbrella or parasol is caused to move longitudinally of the umbrella rod by the action of a spring or elastic member to compel the central upper portion of the cover to assume a canopy shape when the 25 cover is opened.

With these and other objects in view the invention consists in certain novel features of construction, and combinations and arrangements of parts as will be more fully 30 hereinafter described and pointed out in the claim.

In the accompanying drawings—

Figure 1 is a fragmentary view in longitudinal section showing the central portion 35 of the umbrella or parasol when the latter is in open position.

Figure 2 is a view similar to Figure 1, showing the arrangement of parts when the umbrella or parasol is in closed position.

40 Figure 3 is a perspective view of the umbrella or parasol in open position.

In the description hereinafter of our invention, we shall refer to the same as an umbrella with the understanding that this term is used in its broadest sense to include a 45 parasol or any portable analogous device which is utilized either for protection against the rain or the sun.

1 represents the stick of our improved 50 umbrella, to which at a point removed from its end a collar 2 is fixed. This collar 2 may be secured to the rod in any approved manner, and we have illustrated as a securing means a pin 3 projecting through the 55 rod and sleeve, although the invention is, of course, not limited in this particular.

To the fixed collar 2 the ribs 4 are pivotally connected, as shown at 5, and it is to be understood, of course, that the ribs are connected by ordinary stays to a sliding 60 ring or collar, such as is common in the art, and which needs no detail description or illustration.

6 represents the cover of the umbrella. This cover is made in sections, as is customary, and the seams of the sections being located in approximate alignment with the ribs and the cover attached at its outer edge to each of the ribs as is customary in the art.

On the end of the rod 1 we provide a 70 tubular ferrule 7 having a closed outer end 7^a, the ferrule being adapted to move longitudinally on the rod, and a coiled spring or other elastic member 8 is positioned around the stick 1 and interposed between the inner 75 end of the ferrule 7 and the collar 2 and exerts an outward pressure on the ferrule 7.

The ferrule 7 is preferably formed with an annular groove 9 and in this groove 9 the central portion of the cover 6 is 80 secured, preferably by means of flexible strands 10 of metal, silk, or any other material.

In assembling the parts, the cover is reversed and secured in the groove 9 by means 85 of the strands 10, and when inverted, the strands will be enclosed. Around the outside of the ferrule and overlapping the upper central portion of the cover 6, we preferably provide an ornamental ring 90 11, which is preferably made of silk or other material which conforms to the material of the cover itself and gives an ornamental and attractive finish to the same.

In cutting the sections of the cover the inner ends of each section are so shaped that when the umbrella is opened and the ferrule 7 forced outwardly by the spring 8, this central portion of the cover will assume what is known in the art as a "canopy" shape, 100 giving an attractive appearance to the umbrella and yet functioning to prevent rain from entrance around the rod by reason of the construction above described.

The central portion, which we indicate 105 by the reference numeral 12, is maintained taut by the action of the spring 8 when the umbrella is open, but when the umbrella is closed, the cover draws the ferrule inwardly along the rod or stem 1 and serves to tightly 110 compress the spring 8, so that the ferrule has no appreciable movement on the stem and

the umbrella can be used as a walking stick without any noticeable movement of the ferrule. The attachment of the edges of the cover to the ribs insures the inward or downward movement of the ferrule when the umbrella is closed, and the spring 8 insures the outward movement of the ferrule when the umbrella is open to give the desired effect.

10 A disk 14, preferably of silk or other material which conforms to the material of the cover, is located against the outer face of the ribs 4 and between the same and the inner face of the cover 6 and has a central opening 15 to allow it to be positioned around the rod 1 and collar 2. This disk may be perfectly plain or may be ornamented as may be desired.

15 Around the stick 1 against the inner end 20 of the collar 2 a flexible ornamental collar 16 is located and is secured to the ribs 4 and to the disk 14 by stitches or binding strands 17 so as to prevent displacement of the collars in use.

25 It is obvious that the invention is not limited to the particular manner of fastening the collars or the ornamentation relative thereto, but it is desirable to employ such collars to give a neat and attractive appearance to the inside of the umbrella when 30 opened, although they may be omitted, if desired, without departing from the invention.

35 In operation, the ferrule 7 is caused to move outwardly by the spring 8 when the umbrella is opened, to hold the central portion of the cover taut and give the desired canopy shape and, at the same time, the manner of securing the cover to the ferrule 40 renders the cover watertight. When the umbrella is closed, the cover operates to draw the ferrule longitudinally of the rod 1 to compress the spring 8, so that the um-

rella, when in closed position, can be rolled and used without any appreciable movement of the ferrule. 45

Attention is directed to the fact that the collar holding member 16 also cooperates with the flexible member 14 in concealing the spring 8 and in protecting the same 50 from foreign objects, thereby rendering the umbrella highly desirable and salable. Also it is undesirable to have the spring exposed so that foreign objects may strike the same and the provision of the flexible member 14 55 and the member 16 rearwardly of the spring effectively conceals and protects the spring.

Various slight changes might be made in the general form and arrangement of the parts described without departing from the 60 invention, and hence we do not limit ourselves to the precise details set forth, but consider ourselves at liberty to make such changes and alterations as fairly fall within the spirit and scope of the appended claim. 65

We claim:

An umbrella comprising a stick, a collar secured thereon, ribs pivoted to said collar, a cover secured to said ribs, a socketed ferrule slidable on said stick and having connection with said cover, a coiled spring confined between said collar and said ferrule, a strengthening member of the same material as the cover arranged between the cover and the inner portions of the ribs and having a central opening receiving said stick and collar, and a combined collar holding and ornamental member having attached strands joined with the inner portion of said strengthening member, said strengthening member and said collar holding member being arranged rearwardly of said spring for protecting and concealing the same. 70 75 80
